UNITED STATES PATENT OFFICE

2,175,157

CLEANING DEVICE

Arthur A. Nu-Dell, Chicago, Ill., assignor to Nu-Dell Manufacturing Co., Inc., Chicago, Ill., a corporation of Illinois

Application April 14, 1937, Serial No. 136,874

4 Claims. (Cl. 15—152)

This invention relates to a novel cleaning device adapted to clean wallpaper, walls, window shades, upholstered furniture, draperies, and the like.

5 One of the objects of this invention is to provide a cleaning element which can be used in combination with a conventional holder, such as a mop holder, or the like.

A further object of this invention is to provide 10 a core or forming element about which a cleaning substance, such as for example, a sheet of sponge rubber, may be wrapped and firmly secured thereto, so that a firm cleaning surface may be presented.

15 Another object relates to the novel shape of the core which facilitates the use of the device at a large variety of angles against the surface to be cleaned, from 0° to 180°, the benefits of which will be readily appreciated and found 20 necessary in cleaning walls and ceilings, and the angular variation further prevents an entire surface of the cleaning element from immediately becoming saturated with dirt, as is the case with cleaning elements presenting flat surfaces.

25 Other objects relate to the economies of construction, efficiency, novel structure and arrangement of parts, as will be apparent from a consideration of the following description and drawing, wherein:

30 Figure 1 is an elevation of a conventional mop holder, which may be used to clamp and retain my forming core and cleaning element.

Figure 2 is a side view of a preferred form 35 of core or forming element, and,

35 Figure 3 is an end view thereof.

Figure 4 is a perspective view of a sheet of sponge rubber which may form the cleaning element.

Figure 5 is an end view of the core with an 40 edge of the sheet of sponge rubber attached thereto for convenience in application.

Figure 6 is a fragmentary end view of the 45 holder illustrating the seating of the core on the bail of the mop holder, and the manner of application of the sheet of sponge rubber about them prior to being clamped.

Figure 7 is an elevation of the completed 50 cleaning device showing the core and rubber sheet clamped in the holder, and,

55 Figure 8 is an end view thereof.

Figure 9 is a pictorial illustration of an application of the cleaning device.

Referring to the drawing, 10 indicates a mop 55 stick set into the socket 11 of the holder, the

substantially U shaped clamp 12 having a double clamping edge. Secured to the upper edge of the socket is a spring 13, which carries a collar 14 slidable on the mop stick. Pivoted to the collar is the locking lever 16, to the center of 5 which is pivoted the ends of the bail 15. In the form of mop holder shown, the bail 15 is movable towards the clamp 12, which is fixed, and when the locking lever is turned upwardly from the position shown in Figure 1, the bail is drawn 10 towards it to clamp a cleaning element between them, with the assistance of the spring, as shown in Figures 7 and 8.

It is to be understood, however, that while I have shown one form of mop stick and holder 15 in the drawing for the purpose of illustration, I do not wish to be limited thereto, as various forms of holders embodying the same essential elements may be used equally as well. For example, other mop holders which may be obtained 20 on the market as readily as the form shown, have the bail affixed to the handle socket, and have a clamping element which moves towards the bail by means of a screw arrangement, and without a spring. Another form may have a 25 fixed bail and a movable clamp, the clamp being urged towards the bail by means of an extension from the holder socket pivoted at the ends of the bail. It will therefore be understood that in this description of the operation of my invention, 30 that the clamp 12 may be fixed or movable, and that the bail 15 may be fixed or moveable. Further it will be understood that when the bail is referred to, it is meant to particularly define the transversely extending portion thereof which 35 is adapted to extend parallel with the clamp 12 and to be aligned between the edges.

Figures 2 and 3 illustrate a preferred form of core or forming element, which is preferably a solid structure and substantially semi-circular in 40 cross section, although other forms presenting a smooth or curved surface 17, may be used, and a flat base 18 is preferred. Bi-secting the surface 17 and extending longitudinally of the core 45 is a groove or seating slot 19.

The cleaning element per se, may consist of a sheet of sponge rubber substantially rectangular in form illustrated in Figure 4, and it may be attached by staples or in any other convenient manner to one edge of the core base adjacent 50 its center as at 20, shown in Figure 5. This pre-attachment of one edge, while not essential, assists in applying the sheet about the core as will be further shown.

The core may then be seated on the bail 15 by 55

means of the slot 19, as shown in Figure 6, and the rubber sheet wound around the seated core, so that two opposed edges meet adjacent the center of the base 18. In the form of holder shown, the locking lever is then turned upwardly against the handle to draw the seated core and surrounding sheet of sponge rubber against the clamp in locking engagement, or as previously set forth, in other forms of holders, it may be stated that the bail and clamp are closed against each other so that the edges of the cleaning element or sheet of sponge rubber are clamped between the clamp and base of the core.

It will be readily seen that since the handle extends radially from the core in the completed assembly, and due to the curvilinear outer surface of the core, it may be used against a surface to be cleaned at various angles and from various positions with equal efficiency.

While I have shown and described the preferred embodiment of my invention it will be obvious to one skilled in the art that various changes may be made in the details thereof without departing from the spirit thereof, and I do not wish to be restricted thereto except as set forth in the following claims.

What I claim is:

1. A cleaning device comprising the transversely extending bail and head clamping portions of a mop-holder or the like structure, in combination with a core having a central longitudinal slot therein adapted to seat said bail, and a sponge rubber cleaning element adapted to be extended around said core and said seated bail to encircle said core and thereby cover said bail and to be clamped by means of its opposed longitudinal edges onto the core by said head portion.

2. A cleaning device comprising a transversely extending bail and head clamping elements of a mop-holder or the like structure, in combination with a substantially semi-cylindrical core

having a slot bi-secting and extending into the convex face thereof and adapted to be seated on said bail thereby, and a sponge rubber cleaning element adapted to be extended around said core and said seated bail to encircle said core and thereby cover said bail to have its opposed longitudinal edges clamped against the plane surface of said core by means of the head clamping element.

3. A cleaning device comprising the transversely extending bail and head clamping elements of a mop-holder or the like structure, in combination with a substantially semi-cylindrical core having a slot bi-secting and extending into the convex face thereof and adapted to be seated on said bail thereby, and a rectangular sponge rubber cleaning element having one of its longitudinal edges secured to the plane surface of said core, the free edge thereof being adapted to be extended around said core and said seated bail to encircle said core and thereby cover said bail and to be clamped to the plane surface of said core by means of the head clamping element.

4. The combination with a conventional mop-stick or the like structure having transversely extending clamping elements comprising a bail and a clamping head relatively moveable to clamp an object, of a wall cleaning device comprising an elongated core having a substantially semi-cylindrical cross-section and provided with a longitudinal slot extending into and bi-secting its convex surface and seating therein the bail, a rectangular sheet of sponge rubber having one of its longitudinal edges secured to the plane face of said core and being stretched around said core to encircle it and thereby cover the bail, the opposed longitudinal edge of said sheet of sponge rubber being clamped to the plane face of said core by the clamping head.

ARTHUR A. NU-DELL.
